CLAIM

The ornamental design of a bumper car as shown and described.

DESCRIPTION

FIG. 1 is a perspective view of a bumper car showing our new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top elevation view thereof; and,

FIG. 7 is a bottom elevation view thereof.

The broken lines show portions of the bumper car that form no part of the claimed design.

1 Claim, 7 Drawing Sheets
